UNITED STATES PATENT OFFICE.

HENRY M. GREEN, OF LOS ANGELES, CALIFORNIA.

TELESCOPIC-SLEEVE PUMP.

Application filed February 10, 1925. Serial No. 8,235.

To all whom it may concern:

Be it known that I, HENRY M. GREEN, a citizen of the United States, and resident of Los Angeles, Los Angeles County, State 5 of California, have invented new and useful Improvements in Telescopic-Sleeve Pumps, of which the following is a specification.

This invention relates to pumps and especially to reciprocating plungers for deep 10 well pumps.

An object of this invention is to provide a highly efficient, packless plunger pump. An object is to provide a plunger pump having a series of closely, but slidably fitting 15 sleeve members certain of which are fixed to a standing part and certain to the reciprocating or working plunger.

The invention comprises a pump body having elongated sleeve means closely running in and on each other to form a very narrow interstice in which a film of liquid being pumped acts as a barrier to prevent leakage from the pump chamber after the liquid has been entrained in the pump.

20 Further objects and advantages will be made manifest in the following specification of an embodiment of the invention shown in the accompanying drawing; it being understood that modifications, variations and adaptations may be resorted to within the spirit of the invention as here 25 claimed.

Figure 1 is a longitudinal, central section. Figure 2 is a cross section above the stand- 30 ing valve.

The pump shown includes a jacket 2 having a standing valve seat 3 sustaining a suction pipe P and an inlet valve 4 closing on seat 3. Spaced inwardly, concentrically 40 from jacket 2 and screwed onto threads 5 of the seat 3 is a standing, upwardly extending sleeve 6 of any suitable length. These parts constitute the standing body of the pump.

45 The plunger includes a top check valve body 10, with its valve 11, discharging upwardly. The body has exterior threads 12 on which is screwed a sleeve 13 and extending in interior telescoping relation to the 50 standing sleeve 6.

The body 10 also has threads 14 on which is screwed a sleeve 15 spaced inwardly, concentrically of sleeve 13.

55 The sleeves 13 and 15 have a snug but working fit on sleeve 6, and the sleeve 13 may have a working fit on the jacket 2.

It will be seen that the very long lapping fit of the several tubular parts upon each other obviates any requirement of packing material other than that consisting of such 60 film of liquid as may lodge in the very narrow interstice between the sleeves.

What is claimed is:

1. A deep well pump comprising an elongated, cylindrical, standing jacket having 65 an inlet check valve screwed therein and a sleeve screwed on the valve body and projecting above said valve, a tubular top head carrying a check valve controlling the passage therethrough, an outer sleeve having 70 its upper end fixedly secured on said head to move therewith and extending in exterior telescoping relation to said first sleeve, and an inner sleeve operating in interior telescoping relation to the first sleeve, and being 75 rigidly screwed to the said head and within and spaced from the outer sleeve each sleeve being of uniform diameter and working one on the other substantially from end to end.

2. A pump construction comprising a 80 deep well jacket tube having an inlet valve and a standing sleeve projecting above said valve, a plunger device comprising a tubular head carrying a check valve controlling the passage therethrough, said device being provided for discharge above said check valve, a sleeve having its upper end rigidly secured exteriorly of and on said head and extending in exterior relation to said standing sleeve, and a third sleeve operating in interior 85 telescoping relation to said standing sleeve, said head being screwed to the upper end of said third sleeve and suspending the latter within and in spaced relation to said second sleeve; each sleeve being of uniform 90 diameter.

3. A packingless deep well pump comprising a standing, elongated, jacket structure, and a working plunger, and means including elongated tubes having close telescopic fit on each other and being secured to respective plunger and structure parts, whereby to form small working joint interstices in which the liquid pumped will form an effective leak-proof seal the jacket and 100 one tube being screwed onto a standing valve body, and a pair of the tubes being 105 screwed onto a head valve body to work therewith.

HENRY M. GREEN.
